UNITED STATES PATENT OFFICE.

IRA R. SELTZER, OF WATERBURY, CONNECTICUT, ASSIGNOR TO THE GORDON ELECTRIC MFG. CO., OF WATERVILLE, CONNECTICUT, A CORPORATION.

DESIGN FOR A PLURAL-POLE ENTRANCE-SWITCH BASE.

55,090.

Specification for Design.

Patented May 4, 1920.

Application filed June 12, 1919. Serial No. 303,793. Term of patent 14 years.

To all whom it may concern:

Be it known that I, IRA R. SELTZER, a citizen of the United States, residing at Waterbury, in the county of New Haven and State of Connecticut, have invented a new, original, and ornamental Design for a Plural-Pole Entrance-Switch Base, of which the following is a specification, reference being had to the accompanying drawing, forming part thereof.

Figure 1 is a top or plan view of a plural

pole entrance switch base, showing my new design.

Fig. 2 is a reverse plan view.

Fig. 3 is a side view.

I claim:

The ornamental design for a plural pole entrance switch base, as shown.

IRA R. SELTZER.
